Atty.

UNITED STATES PATENT OFFICE.

EDWARD J. JEWELL, OF CHICAGO, ILLINOIS.

DESIGN FOR A STATUE.

58,911.

Specification for Design.

Patented Sept. 6, 1921.

Application filed February 23, 1921. Serial No. 447,328. Term of patent 3½ years.

To all whom it may concern:

Be it known that I, EDWARD J. JEWELL, a citizen of the United States, residing at Chicago, in the county of Cook and State of Illinois, have invented a new, original, and ornamental Design for a Statue, of which the following is a specification, reference being had to the accompanying drawing, forming a part thereof.

In the drawing Figure 1 is a front view showing my new design of statue.

Fig. 2 is a side view thereof.

I claim—

The ornamental design for a statue, as shown.

EDWARD J. JEWELL.
